WARP TYING MACHINE

Max Bär, Augsburg-Göggingen, Germany, assignor to "Knotex" Maschinenbau G. m. b. H., Augsburg-Stadtbergen, Germany, a corporation of Germany

Application May 9, 1951, Serial No. 225,450

Claims priority, application Germany
June 22, 1950

5 Claims. (Cl. 28—49)

1

This invention relates to certain improvements in or relating to warp tying or knotting machines.

In warp knotting machines, pairs of brushes or needles (so-called clips) or mixed groups of brushes and needles are required for doffing or taking off the thread at the top and at the bottom, according as the threads to be knotted are parallelly disposed or crossed. Since in a textile factory a plurality of such take-off mechanisms are occurring, the hitherto known knotting machines have been designed in such a way that their thread doffing means are variable for each of these four different kinds of doffing; to this end, especially the needles and brushes are interchangeable. This interchanging, however, is difficult, since the connecting screws to be removed are of poor accessibility, the screws may be lost and require special tools by the handling of which the sensitive parts of the machine may be damaged. Primarily, however, the correct and true adjustment of these parts after their re-fitting is not ensured, so that the machine in many instances after the exchange does not operate satisfactorily.

In order to eliminate these difficulties, a separate non-variable knotting machine has been developed for each of the four thread doffing mechanisms occurring, which four knotting machines may operate on the same warp tension device. This, however, requires a larger number of these relatively expensive warp tying machines, whose capacity can hardly ever be utilized fully.

It is an object of the present invention to provide a solution of the problem which avoids the drawbacks of the two known types of machines while combining their advantages.

With this and further objects in view according to the present invention the drive for the movement of the machine over the two warp tension devices and for the changing of the movable carriage of the warp tension device as well as for the control and driving instrumentalities of the real thread guiding mechanism are arranged in a universal frame which is common for all thread doffing mechanisms and into which the thread guiding mechanism which is combined into a block, can be inserted so as to be easily interchangeable. Thus all material parts which remain unchanged, such as the drive for the travel of the knotting machine over the two warp tension devices and for the changing of the movable warp tension carriage, as well as for the control and driving members of the thread guide mechanism are provided only once on every machine, the thread grippers and the thread knotted also being arranged on the main frame.

2

On the other hand, the thread guide mechanism, comprising the feeler, the thread doffing mechanism and the thread guide, is manufactured in four different types corresponding to the four different doffing methods and can be interchanged in the main frame by a simple manipulation without requiring skilled labor. The satisfactory operation of the machine remains ensured. To this end, it is merely necessary to adjust a mark on the main frame defining the angular position of the control shaft and a corresponding mark on the block defining the angular position of the driving gear of the thread guide mechanism.

15 The total cost of such a machine with four interchangeable blocks embodying the different take-off mechanisms is substantially less than that of four complete machines. A further advantage consists in that the assemblage of the parts combined in the block, i. e., the thread feeler, the thread take-off mechanism and the thread guide is substantially facilitated compared to the assemblage in a complete universal machine. This is further facilitated by constructing the block in the form of a hollow case accommodating the thread feeler mechanism and at one of its outer sides the thread take-off and thread feeding mechanisms; in this case, a substantial part of the mechanisms is freely accessible.

20 30 It will be understood that my novel machine also offers substantial advantages as regards the cleaning.

Other and further objects, features and advantages of the invention will be pointed out herein-after and appear in the appended claims forming part of the application.

35 In the accompanying drawings a preferred embodiment of the invention is shown by way of illustration and not by way of limitation.

40 45 Fig. 1 is a perspective front view, from the bottom right hand side, of the common standard or universal main frame.

Fig. 2 is a perspective rear view, from the top left hand side of the block unit of a thread guide mechanism, on a larger scale.

The main frame 2 which is U-shaped and provided with bars 1 accommodates an electric motor (not visible) including a gear, and a hand drive, both driving the main shaft 4 through a chain

50 55 3. Mounted on the main shaft 4 is the driving pinion 5 and two eccentrics for the rocking arms 6 and 7. Moreover the driving shaft is operatively connected, through worms and pawls, to the toothed wheel 8 for the feed through the two warp tension devices and to the toothed wheel 9 for

the changing of the movable warp tensioning carriage. Furthermore, the main frame 2 bears the thread gripper 10 and the knotter 11. A guide 12 serves for the reception of the interchangeable block 13 which bears by its recess 14 on the support 15 arranged in the main frame and by the face 16 of the bar 17 on the bridge 18 arranged in the main frame; said bridge being formed with a slot 19 in which is engaged the threaded bolt 20 of the bar 17 which is locked by swinging the bar 17 protruding through a slot 21 of the front shield 22 of the block.

The block 13 bears the driving rod 23 for the thread feeler which serves to feel out, in a well-known manner not shown in detail, the position of the threads above and below a stationary abutment, only the two rearward control edges 24 and 25 of the thread feeler being shown, whose motions are non-positively transmitted to levers arranged in the main frame, which levers may also serve to uncouple the pawl mechanism, which is also well-known and not shown in detail, in the train of the feed gear 8 and/or of the changing gear 9.

The block 13 moreover bears the thread take-off mechanism which is either provided with two needles (so-called clips) or with two brushes (in case of crossed threads) or with a needle on the top side and a brush on the bottom side or with a brush on the top side and a needle on the bottom side (mixed group), such arrangements being well known and not shown in detail. This mechanism, which in the case illustrated is provided with cross slides controlled through eccentric cams 26, 27, is driven by the driving gear 28 meshing in assembled condition with the pinion 5. The marks used for the correct meshing engagement on assemblage of the block and the main frame are not shown in detail.

The thread guide 29, which serves to feed the threads to the thread gripper 10, is moved by the driving rod 30.

Each of the two driving rods 23 and 30 has a link arm 31 or 32 which by its recesses 37 or 38 can be easily hooked into or out of the rocker arms 6 or 7, respectively.

While the invention has been described in detail with respect to a preferred example and embodiment of the invention it will be understood by those skilled in the art after understanding the invention that various changes and modifications may be made without departing from the spirit and scope of the invention and it is intended, therefore, to cover all such changes and modifications in the appended claims.

What is claimed is:

1. In block-type warp tying textile apparatus adapted for effecting any of a plurality of different kinds of doffing operations and having warp tension means, thread guide means, thread feeler means, thread take-off means, thread feeding means, thread gripper means, and thread knotting means, the combination comprising a main frame, main drive mechanism for all said means mounted on said main frame, a detachable unit for each of said different doffing operations, each of said detachable units including the operative components of said thread feeler means, said thread take-off means, and said thread feeding means, locking means for attaching a selected one of said detachable units to said main frame adjacent said driving mechanism, and power transmission means in each said detachable unit and on said drive mechanism for cooperative engagement therebetween with said one of said

detachable units in operating position upon said main frame for driving said operative components in said detachable unit.

2. Block-type warp tying textile apparatus adapted for effecting any of a plurality of different kinds of doffing operations and having warp tension means, thread guide means, thread feeler means, thread take-off means, thread feeding means, thread gripper means, and thread knotting means, the combination comprising a main frame, a motor mounted on said main frame for driving all said means, a main drive shaft connected to said motor, rocker arm and cam means mounted on said drive shaft for transmitting motion from said motor to said thread feeler means and said thread feeding means, gear means connected to said drive shaft for transmitting power from said motor to said thread take-off means and said warp tension means, a detachable unit for each of said different doffing operations, means for detachably mounting a selected one of said detachable units on said main frame adjacent said drive shaft, each of said detachable units including thread take-off means for one of said different doffing operations and said feeler, feeding, and tensioning means, lever means in each said detachable unit for detachable operative engagement with said rocker arm and cam means on said main drive shaft, and gear means in each said detachable unit for detachable operative engagement with said gear means on said main drive shaft.

3. Block-type warp tying textile apparatus adapted for effecting any of a plurality of different kinds of doffing operations and having warp tension means, thread guide means, thread feeler means, thread take-off means, thread feeding means, thread gripper means, and thread knotting means, the combination comprising a main frame, a motor mounted on said main frame for driving all said means, a main drive shaft connected to said motor, rocker arm and cam means mounted on said drive shaft for transmitting motion from said motor to said thread feeler means and said thread feeding means, gear means connected to said main drive shaft for transmitting power from said motor to said thread take-off means and said warp tension means, a detachable unit for each of said different doffing operations, means for detachably mounting each of said detachable units singly on said main frame adjacent said drive shaft, each of said detachable units including thread take-off means for one of said different doffing operations and said feeler, feeding, and tensioning means, lever means in each said detachable unit for detachable operative engagement with said rocker arm and cam means on said main drive shaft, gear means in each said detachable unit for detachable engagement with said gear means on said main drive shaft, and control levers in each said detachable unit actuated by said gear means for controlling the operation of warp tensioning means on said main frame.

4. In block-type warp tying textile apparatus having a main frame and main drive means mounted thereon for effecting the mechanical steps of a warp tying operation, a detachable unit comprising thread feeler means, thread take-off means, and thread feeding means, locking means for mounting said detachable unit on said main frame adjacent said drive mechanism, and power transmission means in said detachable unit having detachable operative engagement with said main drive means to effect power transmis-

sion from said drive means to said unit when said unit is mounted on said main frame.

5. In a warp tying textile apparatus adapted for effecting any of a plurality of different kinds of doffing operations and having thread take-off means, thread feeler means, thread tensioning means, and thread feeding means mounted in a separate detachable unit, the combination comprising a main frame for said apparatus, motor means mounted on said main frame for driving all said means, a main drive shaft mounted on said main frame operatively connected to said motor means, rocker arm and cam means on said drive shaft for operative engagement with said detachable unit transmitting motion from said motor means to said thread feeler means and said thread feeding means in said unit, gear means connected to said main drive

10
15

shaft for engagement with said detachable unit transmitting power from said motor to said thread take-off means and said thread tension means in said detachable unit, locking means on said main frame for receiving and detachably engaging said detachable unit, and control levers on said main frame actuated by cooperating means in said detachable unit for controlling said thread tensioning means, whereby a detachable unit for each said doffing operation may be detachably and operatively engaged with said rocker arm, cam, gear, and lever means for driving and controlling all said means in said detachable unit from said single motor and main drive shaft on said main frame.
